UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

TYPE-GUARD.

1,292,971.

Specification of Letters Patent. Patented Jan. 28, 1919.

Original application filed May 20, 1916, Serial No. 98,853. Divided and this application filed March 27, 1918. Serial No. 224,959.

To all whom it may concern:

Be it known that I, OTTO THIEME, a citizen of the United States, residing at the city of St. Louis, State of Missouri, have 5 invented a certain new and useful Improvement in Type-Guards, of which the following is a full, clear, and exact description, such as will enable others skilled in the art to which it appertains to make and use the 10 same, reference being had to the accompanying drawings, forming part of this specification, in which—

Figure 1 is a side elevational view through the rear end of a calculating machine showing 15 my improved type guard in position thereon.

Fig. 2 is a vertical sectional view through the same.

Fig. 3 is a horizontal sectional view 20 through the same.

Fig. 4 is a side elevational view of the printing segments detached.

Fig. 5 is a detail view partly in section 25 of the inking ribbon guide for the printing segments.

Fig. 6 is a front elevational view of the type segments.

This invention relates to a new and useful improvement in type guards for printing 30 type of calculating machines, and is a division of an application filed by me May 20, 1916, Serial Number 98,853.

In the parent case there is illustrated and described a tally roll attachment for the 35 Moon-Hopkins billing machine including in its structure denominational racks 100 which coöperate with register wheels 119 and 268. Type segments 561 mesh with the rear ends of these racks for the purpose of making a 40 printing impression upon the tally roll strip 600 carried by the laterally adjustable frame 503 which, when vibrated, causes its platen to press the paper against the inking ribbon in the printing line and effect a printing 45 impression from the tally roll segments. The record thus made may be of the items or of the totals indicated by the register wheels 119 or 268.

Means are also shown in the parent case 50 for laterally adjusting the frame 503 whereby the records made on the tally strip may be arranged in column order.

Means are also disclosed in the parent case for tabulating the frame 503 effecting

the feed of the tally roll strip, returning 55 the frame 503 to its normal or starting position, and controlling the several operations of the frame 503 automatically by adjustable stops on the main paper carriage identified with the words-printing mechanism of 60 the typewriting mechanism, not herein shown. These form no part of my present invention, as this application is confined to the construction and method of operation of the type guards which coöperate with the 65 tally roll printing segments.

As the platen 505 carried by the vibrating frame 503 extends entirely across the printing line in any lateral position of the frame 503, and as the zero printing type on 70 the segments 561 are normally in the printing line, it follows that some means must be provided to prevent the printing of zero type to the left of any number recorded, and likewise means must be provided for uncovering 75 the zero type to the right of any digit printed, so that if the number "1250" were to be printed by the tally roll segments, it would appear as "1250" the zeros to the left being blinded and the zero at the right being automatically uncovered, although its controlling rack bar would remain stationary.

Whenever the denominational racks 100 are moved forward, they position the segments 561 so as to present appropriate printing type in the printing line, and if after said type are so positioned, the frame 503 is vibrated so as to cause the tally roll strip 600 to be pressed against the inking 90 ribbon arranged above the type, a printing impression will be made, all as described in said parent case.

Each of the type segments 561 carries printing type 562 on its periphery, and each 95 of said printing segments in addition is provided with a shoulder 563 on its hub. 564 indicates a rocking T-shaped lever, there being one of such levers for each printing segment. each lever being independently 100 held rearwardly against a stop bar 564 by means of a spring 565. The rearward extension or shoulder of this T-shaped lever 564 is thus caused to bear against the shoulder 563 on the hub of the printing segments. 566 indicates a thin, flat, steel type guard carried by the upper end of lever 564 and extending rearwardly in a curved line over 105

the type 562, the rear or free end of said guard being bent upwardly so as to provide a space over the zero type for the inking ribbon 600^a. Whenever the racks 100 move 5 forwardly, they will cause the printing segments 561 to be rocked rearwardly, and consequently the zero of each operated segment will be moved rearwardly below the inking ribbon so as to successively bring printing 10 characters 1, 2, 3, 4, etc., opposite the printing line. Upon the initial rearward movement of the segments 561, the shoulder 563 will rock the T-shaped lever 564 forwardly, thus carrying with it the guard plate 566 15 which will uncover the type in the printing line in readiness to receive the impression stroke of the platen. Each one of the T-shaped levers 564 is provided with a bent portion 567 (see Fig. 6) which extends behind the next adjacent T-lever of lower order so that when a segment 561 of any 20 higher order is operated, notwithstanding the fact that the racks 100 of lower order are not operated, the T-shaped levers identified with the printing segments in the lower orders will be rocked forwardly by means of these projections 567 so that the zero type in the printing line in such lower orders will be exposed to make a printing impression. The guards over the zero type in the 25 higher orders above the highest digit in the number being recorded, will not be moved, and consequently, will bind the zero type in such higher orders. When the type have 30 been brought to the printing line and a printing impression is made, the restoration of the racks will cause the printing segments to be returned to their normal or home position in which the zero type are in the 35 printing line. In order to avoid excess movement of the T-shaped levers 564, the hubs of the printing segments below the shoulders 563 are preferably formed concentric so that after the "1" type has been 40 positioned to the printing line, the successive movement of the segments in bringing the "2" "3" and "4" type to the printing line, will cause the rear end of the T-shaped lever to ride on the concentric portion of the 45 hub, and thus the type guard in exposing the type in the printing line will not be given an excess or unnecessary forward movement. Of course when the segment is restored and the hub 563 passes beneath the 50 rearward extension of the T-shaped lever, said T-shaped lever will move rearwardly until arrested by the bar 564^a, in which position the type guard will cover the zero type.

As shown in Figs. 5 and 6, there is a ribbon guide 616, there being one of said ribbon guides arranged at each side of the printing type so as to guide the ribbon over the printing line, *i. e.*, the line in which the zero type are normally in printing position. These 65 ribbon guides are mounted on the ends of

plates having slot and pin connection with arms 617 and are normally held outwardly by means of springs 618 so that when the platen makes a printing impression, these guides will yield slightly and then lift the 70 inking ribbon away from the printing type so as to permit their free restoration and at the same time enable the inking ribbon to remain in its printing line position. I have not herein disclosed any means for 75 feeding the inking ribbon, as the same is set forth in the parent case before mentioned.

What I claim is:

1. In an apparatus of the character described, the combination of denominational 80 type segments whose zero type are normally in the printing line, a type guard normally covering said zero type, and means for moving said type guard upon the actuation of its companion segment whereby the type 85 positioned in the printing line will be uncovered.

2. In an apparatus of the character described, the combination of denominational 90 printing segments whose zero type are normally in the printing line, flexible type guards which normally cover said zero printing type, and means operated by said type segments whereby said type guards are moved to uncover the type in the printing 95 line of the actuated segment.

3. In an apparatus of the character described, the combination of denominational 100 printing segments whose zero type are normally in the printing line, flexible type 105 guards which normally cover said zero printing type, means operated by said type segments whereby said type guards are moved to uncover the type in the printing of the actuated segment, and connections between the said type guards whereby the zero type to the right of any actuated segment will be exposed.

4. In an apparatus of the character described, the combination of denominational 110 printing segments whose zero type are normally in the printing line, flexible type guards which normally cover said zero type, yielding ribbon guides for supporting an inking ribbon between said zero type and 115 said type guards, means for retracting said type guards to uncover said ribbon and expose the type in the printing line, and a platen for effecting a printing impression on a strip of paper over the exposed type 120 only.

5. The combination with a rocking printing segment, of a type guard holder normally in engagement therewith so as to cover the type on the printing line, and means whereby when the digits on said segment are moved to printing position in one direction, said type guard will be moved in the opposite direction to expose the type on the printing line. 130

6. The combination of a printing segment having a projection, a rocking type guard support coöperating with said projection and movable in an opposite direction to the movement of said printing segment when the latter is moved, and a type guard carried by said support, the free end of which is normally located over the type in the printing line.
- 5 7. The combination of a printing segment having a shouldered hub portion and a spring-pressed type guard support coöperating therewith, and a type guard carried by said support.
- 10 8. The combination of independently op-
erated denominational type segments, guard supports operated thereby, there being one of said supports for each of said segments, and flexible type guards carried by said support, the free ends of which normally cover 20 the type in the printing line, means whereby said type guard supports are actuated to uncover the type in the printing line whenever its companion type segment is operated, and means whereby said type guard supports 25 may be operated independently of any movement of said type segments.

In testimony whereof I hereunto affix my signature this 21st day of March, 1918.

OTTO THIEME.
